PACKAGE OPENING DEVICE

Otto Anderson, Paulsbo, Wash.

Application December 21, 1937, Serial No. 181,050

4 Claims. (Cl. 229—51)

My present invention relates to means for opening packages, such as those used for cigarettes wherein the materials used in creating the package are not self-supporting and rely upon the 5 tight nesting of the contents to maintain the shape of the package.

My device is especially useful for opening the type of package used as a container for twenty cigarettes but it may also be used for opening 10 packages of other materials, particularly those that are encased in the transparent sheet covering materials in which an opening is so difficult to start but, once effected, the covering can be torn quite readily.

15 It is for such packages that my device finds particular application in that it can be easily encased in the package at the time the same is formed and is so inexpensive as not to add appreciably to the cost of the package.

20 Further, my device is of a size, normally, to cover approximately one end of the package and when so constructed provides a reinforcement or supporting means for the end of the package that prevents crushing of the same with the 25 resultant mutilation of the contents.

A further object of my present invention is to 30 provide means that will assure uniform opening of a package, that can be effected by one hand, even when gloves or mitts are worn on that hand.

Still a further object of my invention is to 35 provide means that will definitely hold the torn, covering materials in an unobtrusive manner and will provide that the unopened end of the cigarette, or other, package will be so supported that it will not be damaged.

Another important object of my present invention is to provide means that is adjustably under 40 the control of the user, that will regulate the manner of dispensing the package, and can be used to hold part of the contents back in the uncollapsed portion of the package so that the cigarettes, for instance, may by mutual support, provide against the flattening or crushing of themselves.

45 Other and more specific objects will be apparent from the following description taken in connection with the accompanying drawing, wherein

Figure 1 is a top plan view of an opening device made after the teachings of my invention.

Figure 2 is a longitudinal, sectional view through my device.

Figure 3 is a view from the right hand end of Figure 1.

Figures 4 and 5 are cross-sectional views taken along the similarly numbered lines of Figure 1.

Figure 6 is a top plan view of a cigarette package which is shown in section, disclosing my opening device in the position it assumes during the 5 transportation of the package.

Figure 7 is a fragmentary view, in perspective, showing the top of a package, sealed in the conventional manner, with my device entirely concealed.

Figure 8 is a perspective view taken in the same sense as Figure 7 but illustrating the manner in which the initial step is taken in the opening of a cigarette package.

Figure 9 illustrates in fragmentary, perspective 15 view an opened package of cigarettes with my opening device in its final position holding the torn end portion of the package down against the top of the package where it is out of the way.

Figure 10 is a perspective view similar to Figure 9 but illustrating the same with the cigarette control device folded back with the opening portion of the same.

Figure 11 is a perspective view taken in the same sense as Figures 9 and 10 but showing my 25 cigarette control device as bent downwardly forcing the cigarettes back into the unmutilated portion of the cigarette package.

Referring to the drawing, throughout which like reference characters indicate like parts, 12 30 designates generally my opening device. The overall length of my opener and the width thereof should conform to that of the package in which it is to be used. At one end the corners as at 14 should be rounded or given whatever shape 35 required to fit snugly into the corners of the package. The opposite end is provided with a rather blunt point 16 providing the two cutting edges 18 and 19. The pointed end of my opening device is curved after the showing in Figure 3 with the 40 extreme edges given a little more abrupt curve as indicated at 20 and 21. These corners are to provide in effect cutting edges terminating in points to pierce and cut the several layers of materials making up the package so that the margin of the package as indicated at 23 and 24 will 45 be cut reasonably clean.

Struck out of the body of blank 12, at the pointed end of the same, is the cigarette control tongue 26. This is provided with a curved outer 50 face as 28, substantially straight sides 29 and a reduced neck portion at 30. The base of this reduced neck portion as 32 is substantially on a line with the end of the curved up lips 20 and 21 which extend substantially to points 34 and 55

35. In this manner a natural line of bending is provided in that the material of tongue 26 is of reduced section at this point and the body 12 has minimum resistance at this same point owing to the fact that the strengthening of plate 12, due to the curved section, leaves off at this point. This construction is of material advantage when the opening of a cigarette package is undertaken.

Method of operation

- 10 When cigarettes, or other materials, are packaged the opener member 12 is inserted therein underneath the end covering material which is then folded around the same so as to entirely hide it from view. When it is desired to open a package the same is grasped, as shown in Figure 8, by supporting it at the rear as by the fingers shown at 37 and pressing the thumb 38 in a substantially horizontal manner somewhat below the upper margin of the package. As the thumb is pressed inwardly, to a degree less than that shown in the exaggerated Figure 8, point 18 first breaks through the layers of covering material. The pressure by the thumb is then changed to an upward thrust forcing the upturned lips 20 and 21 against the sides 23 and 24 and as the same is forced upwardly, the end of the package, including the revenue stamp at 40, is cut away after the showing of Figures 9, 10, and 11. The final action with the thumb is to press the pointed end of the opener 12 back and down until it assumes the position shown in Figure 9. When so done substantially one-half of the package has been opened, the material removed from the open end portion is clamped between the two ends of the opener and held in position out of the way. The cigarette control tab 26 is normally left in the position shown in Figure 9. Owing to the curve occurring at 28 and to pressing inwardly at the opposite corners 42 and 43, the end walls will be forced out sufficiently so that a single cigarette can be dispensed at a time. If this is not desirable particularly when filling a cigarette case and the like, tab 26 can be bent back and lie within its original opening 45 as shown in Figure 10 and thus permit ready access to about forty percent of the package. This action usually releases enough to fill the average small cigarette case. If it is desired to preserve the

remainder of the cigarettes without distortion the tab 26 can be bent downwardly after the showing of Figure 11 so as to hold the remaining, approximately one-half of the cigarettes, well back into the unopened part of the package where by their own combined strength they are able to preserve the original outline of the package and thus are able to resist distortion when carried about. When these cigarettes are desired it is a simple matter to turn the tab up after the showing of Figure 10 where it is entirely out of the way.

The foregoing description and the accompanying drawing are believed to clearly disclose a preferred embodiment of my invention but it will be understood that this disclosure is merely illustrative and that such changes in the invention may be made as are fairly within the scope and spirit of the following claims.

I claim:

1. An opener for use within a paper receptacle comprising a flat sheet of pliant material having a transverse cutting edge at one end, said end being concavo-convex in cross section and having reinforced longitudinally extending edges.
2. An opener for use within a paper receptacle comprising a sheet of pliant material having a transversely extending, pointed, cutting edge at one end, said end being concavo-convex in cross section, and inturned reinforcing flanges extending along the longitudinal edges of said end.
3. An opener for use within a paper receptacle comprising a sheet of pliant material having an intermediate transversely extending weakened portion adapted to be bent, a cutting edge at one end of the sheet, and upturned lips extending along the longitudinal edges from the cutting edge to said intermediate weakened portion.
4. An opener for use within a paper receptacle comprising a sheet of pliant material having an intermediate transversely extending weakened portion adapted to be bent, a cutting edge at one end of the sheet, parallel longitudinally extending reinforcing flanges at the edges between said cutting edge and weakened portion, and a foldable tongue struck from said end portion having a base integral with the weakened portion.

OTTO ANDERSON.
